UNITED STATES PATENT OFFICE

105,991

DESIGN FOR A CRAVAT HOLDER OR SIMILAR ARTICLE OF JEWELRY

Ira J. C. Holland, San Angelo, Tex.

Application July 3, 1936, Serial No. 63,644

Term of patent 14 years

To all whom it may concern:

Be it known that I, Ira J. C. Holland, a citizen of the United States, residing at San Angelo, in the county of Tom Green and State of Texas, have invented a new, original, and ornamental Design for a Cravat Holder or Similar Article of Jewelry, of which the following is a specification, reference being had to the accompanying drawing, forming a part thereof.

Figure 1 is a front elevation of a cravat holder or similar article of jewelry showing my new design, and

Figs. 2 and 3 are a side elevation and a perspective view, respectively, of the pendant portion of the article of jewelry shown in Fig. 1, parts of the chain being broken away for convenience of illustration.

I claim:

The ornamental design for a cravat holder or similar article of jewelry, as shown and described.

IRAJ. C. HOLLAND.
